UNITED STATES PATENT OFFICE.

FRANK KLOUSNITZER, OF CRAFTON, PENNSYLVANIA.

DESIGN FOR A DOLL HEAD.

Application filed April 13, 1923. Serial No. 5,810. Term of patent 7 years.

To all whom it may concern:

Be it known that I, FRANK KLOUSNITZER, a citizen of the United States, residing at Crafton, in the county of Allegheny and State of Pennsylvania, have invented a new, original, and ornamental Design for Doll Heads, of which the following is a specification.

Referring to the accompanying drawing forming a portion of this specification:—

What I claim is:—

The ornamental design for a doll head as shown.

In testimony whereof I affix my signature.

FRANK KLOUSNITZER.
